UNITED STATES PATENT OFFICE.

JOHN KIRKBRIDE, OF ESCANABA, MICHIGAN.

POCKET MATCH BOX.

Application filed October 11, 1921. Serial No. 506,990.

To all whom it may concern:

Be it known that I, JOHN KIRKBRIDE, a subject of King of Great Britain, residing at Escanaba, in the county of Delta and State 5 of Michigan, have invented certain new and useful Improvements in Pocket Match Boxes, of which the following is a specification.

My invention relates to receptacles for such articles as matches, cigars or cigarettes, 10 and the main object of the invention is to provide receptacles of this kind that are of a convenient size for carrying in the pocket without making it bulky.

Another object of the invention is to so 15 construct the receptacles that only one of the articles, as for instance a match, is delivered at a time, and still another object is to make the interior of the receptacle open for inspection to ascertain if it needs refilling.

20 In the accompanying drawing one embodiment of the invention has been illustrated, and

Figure 1 shows a pocket match box in a perspective view opened for removing one 25 match;

Figure 2 is a longitudinal sectional view along line 2—2 of Figure 1;

Figure 3 is a cross section of Figure 2 along line 3—3 thereof; and

30 Figure 4 is a similar cross section of the match box slightly modified.

The match box is constructed with two side walls 10, two end walls 11 and 17, and top and bottom walls 12.

35 As best seen in Figures 2 and 3 I prefer to provide a match box with two chambers and for this reason I furnish a partition 13 in the middle of the box. This divides the box into an upper and a lower chamber. These 40 chambers are only deep enough to hold one layer of matches and a convenient size of match box for practical purposes has been found to be of the size to contain eight matches in each chamber. If there was room 45 for more than one layer of matches in each chamber they might cross each other and prevent the easy removal of one match at a time.

In case of cigar or cigarette boxes it might 50 be preferable to have only one chamber in order not to make the box too bulky or thick.

As best seen in Figures 1 and 2 the top and bottom of the box have windows 14 which

on the inside are covered with a suitable transparent sheet of material such as glass 55 or mica 15.

In the construction illustrated in the first three figures, the top and bottom walls are flanged over the edges of the end and side walls and may be soldered to them on all 60 sides with the exception of one end. At this end the flanges 16 are open, that is, they are spaced slightly from the end wall 17 to form guides for a shutter 18 which is able to slide in both directions across the match 65 box. As will be seen in Figure 1, these flanges 16 terminate a short distance from one corner of the box so as to form abutments 19 which are intended to engage with small nobs or projections 20 provided at the 70 corresponding corners of the shutter 18. It will be noted that these abutments 19 are attached at diagonally opposite corners of the end wall 17, and the reason is, that a small aperture 21 large enough for the passage 75 of one match is provided at each of these corners. The shutter 18 being of the same width as the match box, it will evidently close both of these apertures or passages 21 when it is shut and only open one of them 80 when it is pushed to one side.

The modification shown in Figure 4 differs only from the above described construction by the provision of corner angles 25 along the edges of the box which may be 85 soldered or in any other manner connected to the end and side walls of the box. These angles are provided with grooves 26 for carrying the top and bottom plates 12 and the transparent sheet 15. 90

Instead of either of these constructions I may stamp the box out of one sheet of metal, in which case one end would have to be attached separate to the box.

A roughened surface 28 is provided at a 95 convenient place in the side or top of the box for striking the matches on.

In order to fill the match box it should be held upright and slightly tilted so that one of the apertures 21 will be uppermost and 100 the shutter in that case pushed downwardly to permit access to the aperture in question. One match is now inserted through the aperture at a time and the most practical way is to let the small end of the match enter first. 105 The matches will then fall down to the lower

side of the box until it is completely filled, whereupon the other chamber of the box is similarly filled and the shutter 18 closed.

In order to remove a match, the shutter is drawn to one side and the box tilted about 45° to the horizontal with the open aperture lowermost. By slightly tapping on the match box, the match at that time at the bottom of the box, will gradually come out 10 through the aperture.

As already stated, for boxes intended for cigars or cigarettes only one chamber will be needed and as a consequence only one opening will be provided for removing the contents, but a striking place for matches might be furnished on these boxes as well as on the match boxes and I claim my invention as applying to these kinds of boxes as well as to match boxes.

Having thus described the invention what is claimed as new is:

1. A pocket match box comprising a flat rectangular receptacle, a partition within said receptacle dividing it into two chambers closed on all sides, an aperture slightly larger than the cross section of the match being provided for each chamber at diagonally opposite corners of one of the end walls of said box, a cover for both of said apertures, and means for permitting a limited sliding motion of said cover to both sides in transverse direction of said box.

2. A pocket match box comprising a flat rectangular receptacle, a partition within said receptacle dividing it into two chambers closed on all sides, an aperture slightly larger than the cross section of the match being provided for each chamber at diagonally opposite corners of one of the end walls of said box, a cover for both of said apertures, the top and bottom walls of the box being extended beyond one end thereof and bent to form guides for said cover, said guides terminating adjacent their corresponding apertures to form abutment surfaces and a stop member at each end of said cover adapted to engage with said abutment surfaces to limit the motion of said cover.

3. A pocket match box comprising a flat rectangular receptacle, a partition within said receptacle dividing it into two chambers closed on all sides, an aperture slightly larger than the cross section of the match being provided for each chamber at diagonally opposite corners of one of the end walls of said box, a cover for both of said apertures, the top and bottom walls of the box being extended beyond one end thereof and bent to form guides for said cover, said guides terminating adjacent their corresponding apertures to form abutment surfaces and a stop member at each end of said cover adapted to engage with said abutment surfaces to limit the motion of said cover, and windows being provided in the walls of the box.

4. A pocket match box comprising a flat rectangular receptacle, a partition within said receptacle dividing it into two chambers closed on all sides, an aperture slightly larger than the cross section of the match being provided for each chamber at diagonally opposite corners of one of the end walls of said box, a cover for both of said apertures, the top and bottom walls of the box being extended beyond one end thereof and bent to form guides for said cover, said guides terminating adjacent their corresponding apertures to form abutment surfaces and a stop member at each end of said cover adapted to engage with said abutment surfaces to limit the motion of the cover, and striking surface for matches being provided on the walls of the box.

5. A pocket match box comprising a flat rectangular receptacle, a partition within said receptacle dividing it into two chambers closed on all sides, an aperture slightly larger than the cross section of the match being provided for each chamber at diagonally opposite corners of one of the end walls of said box, a cover for both of said apertures, the top and bottom walls of the box being extended beyond one end thereof and bent to form guides for said cover, said guides terminating adjacent their corresponding apertures to form abutment surfaces and a stop member at each end of said cover adapted to engage with said abutment surfaces to limit the motion of said cover, and striking surface for matches and windows being provided in the walls of the box.

6. A pocket match box comprising a flat rectangular receptacle, a partition within said receptacle dividing it into two chambers closed on all sides, an aperture slightly larger than the cross section of the match being provided for each chamber at diagonally opposite corners of one of the end walls of said box, a cover for both of said apertures, the top and bottom walls of the box being extended beyond one end thereof and bent to form guides for said cover, said guides terminating adjacent their corresponding apertures to form abutment surfaces and a stop member at each end of said cover adapted to engage with said abutment surfaces to limit the motion of said cover, and grooved members along the edges of the side walls and the end walls of the said box adapted to receive the corresponding edges of the top and bottom walls.

7. A pocket match box comprising a flat rectangular receptacle, a partition within said receptacle dividing it into two chambers closed on all sides, an aperture slightly larger than the cross section of the match being provided for each chamber at diagonally opposite corners of one of the end walls of said box, a cover for both of said apertures, the top and bottom walls of the

box being extended beyond one end thereof and bent to form guides for said cover, said guides terminating adjacent their corresponding apertures to form abutment surfaces and a stop member at each end of said cover adapted to engage with said abutment surfaces to limit the motion of said cover, grooved members along the edges of the side walls and the end walls of the said box

adapted to receive the corresponding edges 10 of the top and bottom walls, windows and striking surfaces for matches being provided on said top and bottom walls and sheets of transparent matter suspended across said windows.

15

In testimony whereof I affix my signature.

JOHN KIRKBRIDE. [L. s.]
